UNITED STATES PATENT OFFICE.

CHARLES WITHERS BURTON, OF VANCOUVER, BRITISH COLUMBIA, CANADA.

OIL-BURNER.

1,105,401.

Specification of Letters Patent. Patented July 28, 1914.

Application filed March 7, 1913. Serial No. 752,659.

To all whom it may concern:

Be it known that I, CHARLES WITHERS BURTON, of the city of Vancouver, in the Province of British Columbia, Canada, have ⁵ invented certain new and useful Improvements in Oil-Burners, of which the following is the specification.

My invention relates to improvements in oil burners and the object of the invention ¹⁰ is to devise an oil burner for use in boiler furnaces and the like, which shall deliver the oil into the furnace immediately after it has been atomized, and thus obtain the maximum efficiency from the oil and a smoke- ¹⁵ less combustion in the furnace. I attain this object by the means illustrated in the accompanying drawings in which:

Figure 1, is an outside elevation of the burner nozzle. Fig. 2, is a longitudinal section of the burner nozzle on the center line. Fig. 3, is a view looking on the point of the nozzle. Fig. 4, is an outside elevation of the burner nozzle cap. Fig. 5, is a longitudinal section of the cap on the center line. Fig. ²⁵ 6, is a longitudinal section of the complete burner assembled. Fig. 7, is an outside elevation of the same.

Similar letters refer to similar parts throughout the several views.

³⁰ A is my oil burner.

A' is a nut formed at the back end of the burner.

B is an externally threaded portion extending from the nut A'.

³⁵ C is a reduced smooth tapered portion extending from the portion B and terminating in a further reduced portion E having an annular groove D formed therein.

F is an interiorly threaded orifice formed ⁴⁰ centrally and extending longitudinally through the nut A' to a point intermediate of its length.

G is a reduced orifice extending from the threaded portion F to a point on a line with ⁴⁵ the upper wall of the groove D.

H are orifices extending from the orifice G through the portion E into the groove D. The holes H provide an outlet from the interior of the nozzle.

⁵⁰ J are spiral grooves cut through the outer wall of the groove D for a purpose which will hereinafter appear.

K is a cap formed with an interior tapered periphery L corresponding to the ⁵⁵ taper of the tapered portion C of the nozzle as shown particularly in Fig. 6.

M is a small orifice extending through the cap K preferably centrally and in alignment with the center of the nozzle formed by the tapered portion C. The cap K fits on the ⁶⁰ tapered portion C of the nozzle as above described forming an atomizing chamber M' surrounding the inner reduced end of the nozzle into which the orifices H lead. The atomizing action is further increased by providing spirally-cut grooves J in the end of the reduced portion E as shown in Fig. 1. The space M' so formed is sufficiently large to allow of the proper atomizing of the oil after it leaves the hole H, that is to say, ⁷⁰ when the burner is assembled, the space or distance between the bottom of the recess L and the extreme end of the nozzle is fully equal to the diameter of the outlet hole M.

N is a securing nut provided with an internal thread N' which is threaded on to the exterior threaded portion of the nut A'.

O is an annular rabbet groove formed around the cap K and N' is an annular flange extending inwardly from the nut N ⁸⁰ and fitting into the rabbet groove O. By tightening the securing nut N the cap K may be drawn tight up on to the tapered end C of the nozzle.

In action, the burner is screwed on, ⁸⁵ inside the furnace to the supply pipe leading off the main pipe line which feeds the oil to the burners, this supply pipe being screwed into the screwed recess F provided in the burner for this purpose. The oil feeding ⁹⁰ through the supply pipe, enters the recess F, as indicated by the arrow points in Fig. 6, passes through the hole G, and thence through the outlets H. It then enters the spirally cut grooves J, and passing through them, is given the spiral or rotary motion necessary for atomizing it. As soon as it leaves these grooves J, in its atomized state, it immediately passes through the outlet M in the cap into the furnace.

¹⁰⁰ It will thus be seen that I have devised an oil burner which will deliver the atomized oil into the furnace immediately after it has been atomized, and in which the atomized oil will have no chance to recover any part of its density before leaving the burner, as happens in oil burners where the atomizing space is too large. Thus, by delivering the oil into the furnace immediately after it has been atomized, the greatest efficiency is obtained from it, while at the same time the combustion is smokeless.

What I claim as my invention is:

An oil burner comprising a nut having an externally threaded reduced portion, a reduced tapered portion and having an annular groove in said reduced tapered portion and a central orifice extending through the nut to a point on a line with the exterior wall of the annular groove and having peripheral openings extending from the 5 interior of the central orifice into the groove, spiral ways extending through the exterior wall of the groove, a cap having a tapered interior periphery fitting the outer end of the tapered exterior periphery of the nut,

and forming an atomizing chamber having 15 an orifice leading therefrom, said cap having an annular rabbet formed thereon, and a securing nut extending around the cap and engaging therewith and with the thread of the nut, said securing nut having an annular flange fitting in said rabbet as and for the purpose specified. 20

Dated at Vancouver, B. C., this 14th day of February, 1913.

CHARLES WITHERS BURTON.
